UNITED STATES PATENT OFFICE.

HARRY FISHER, OF NEOGA, ILLINOIS.

PRICE-SCALE.

SPECIFICATION forming part of Letters Patent No. 557,064, dated March 24, 1896.

Application filed April 19, 1895. Serial No. 546,331. (No model.)

To all whom it may concern:

Be it known that I, HARRY FISHER, of Neoga, in the county of Cumberland and State of Illinois, have invented a new and Improved Computing-Scale, of which the following is a full, clear, and exact description.

The invention relates to computing-scales which give the value of an article at the given price per pound or other unit, and which price is varied by the operator manipulating the scales.

The object of the present invention is to provide a new and improved computing-scale, which is simple and durable in construction, very effective in operation, reliable and always in proper balance.

The invention consists principally of a movable point of connection between the weighing-beam and the weighing-frame.

The invention further consists of a movable weight for automatically preserving the balance of the beam throughout all the changes of the connection between the weighing-beam and the weighing-frame.

The invention also consists of certain parts and details and combinations of the same, as will be fully described hereinafter, and then pointed out in the claims.

Figure 1 is a front elevation of the improvement. Fig. 2 is a sectional plan view of the same on the line 2 2 of Fig. 1. Fig. 3 is an enlarged sectional front elevation, on the line 3 3 of Fig. 4, of the connection between the weighing-beam and the frame-platform, and

Fig. 4 is a transverse section of the same on the line 4 4 of Fig. 3.

The improved computing-scale is provided with the usual base A, on which is erected a frame A' supporting standards A², formed in their upper ends with bearings A³ engaged by the knife-edges B² of a rod B', forming part of the scale-beam B, supporting at one end a weight-carrier C, adapted to receive the usual weights D.

On the beam B is fitted to slide a poise E adapted to indicate in the usual manner on the graduation B³, so as to indicate the proper weight of the article to be weighed, it being understood that the weights D indicate the hundreds-weight and the poise E indicates the units-weight up to 100.

On the rod B' and on the side of the knife-edge B² opposite to that on which the weights D are located, is fitted to slide a sleeve F, carrying knife-edges F' projecting into loops G' formed on arms G², extending upwardly from a second sleeve G mounted to slide longitudinally on the middle portion of the frame H, made U-shaped, and connected with the scale-platform arranged in the base A in the usual manner. The frame H has its side arms H' fitted to slide in suitable bearings A⁴ and A⁵, fastened to the base-frame A, as plainly indicated in Fig. 1.

The under side of the sleeve G is adapted to be engaged by a shoe I, preferably made semicircular, as is plainly indicated in Fig. 4, and secured on the upper end of a stem I', fitted to slide vertically in a bearing J' formed at or near the middle of a carriage J, having its wheels J² mounted to travel in slots K' of guide-rails K, attached to the top of the frame A. The stem I' carries at its lower end a spring I², resting with its upper end on the under side of the carriage J and with its lower end on a collar I³, secured or formed near the lower end of the said stem I'. The latter is provided near its upper end with a collar I⁴, adapted to be seated on the top of the bearing J' to limit the downward movement of the stem I' and its sleeve I. A lever I⁵ is pivotally connected with the extreme lower end of the stem I', and this lever is fulcrumed at J³ on one end of the carriage J, as is plainly illustrated in Figs. 1 and 3.

Now it will be seen that by the arrangement described the connection between the scale-beam B and the frame H of the platform is made in such a manner that the said connection can be shifted longitudinally on the beam B by the operator manipulating the lever I⁵, so that a variation can be had at any time between the weight of the scale-beam B and the point of connection between the scale-beam and the platform-frame H. When the operator presses on the outer end of the lever I⁵, he causes the stem I' to slide upward, so as to move the shoe I in engagement with the sleeve G, and as the said shoe I is pivotally connected by arms L with a second shoe L', adapted to engage the sleeve F, both sleeves G and F are moved simultaneously, so that

the operator, upon operating on the lever I^5 , causes the carriage J , and consequently the sleeves G and F , to travel forward or backward on the frame H and rod B' , according 5 to the push or pull given to the lever I^5 .

On the carriage J is formed a stud J^4 , on which is mounted to turn loosely a disk N , adapted to roll on the top surface A' of the base-frame A , so that as the said disk N turns 10 the carriage J is moved forward or backward in its bearings in the rails K . A pointer O which projects upon the circular graduation N' on the disk N is supported by an arm O' , attached to the carriage J .

Now it will be seen that the graduation N' , which determines the price per pound or other unit, is indicated on the fixed pointer O forming part of the traveling carriage J , so that the operator on shifting the latter can set 20 the said disk on the pointer O to any price per pound or other unit of the article to be weighed.

In order to balance the weight of the connection between the beam B and the frame 25 H , I provide the following device: On the rod B' , on the opposite side of the knife-edge B^2 to that on which the sleeve F is located, is fitted to slide a weight P connected at its lower end at one side with a rope Q extending over a 30 pulley R on the end of the beam B next to the weights D . The rope Q extends loosely through an opening in the weight P to connect with a hook on one end of the sleeve F , and the other end of the latter is connected 35 with a second rope Q' passing over a pulley R' journaled on the other end of the beam B , as plainly indicated in Fig. 1. The rope Q connects with the weight P on that end opposite to the one on which the rope Q is attached.

Now it will be seen that when the sleeve F is shifted, as previously described, by the operator manipulating the lever I^5 , then the weight P will move toward the knife-edge B^2 45 at the time the sleeve F moves from the opposite side of the rod B' toward the same knife-edge B^2 , and when the said sleeve moves outward away from said knife-edge B^2 then the weight P likewise moves outward away from 50 the said knife-edge. Thus the weight of the connection between the rod B' and frame H is at all times counterbalanced by the weight P moving in unison with the sleeve F on the rod B' .

The beam B^3 is provided in addition to its 55 graduations with suitable figures representing the prices of various goods, and it will be seen that the price of any particular article will be automatically indicated by the poise 60 E and its position on the beam.

Having thus fully described my invention, I claim as new and desire to secure by Letters Patent—

1. In a computing-scale, a weighing-beam, 65 a platform, a connection between the weigh-

ing-beam and platform-frame, and comprising a sleeve movable on the said weighing-beam, a sleeve movable on the said platform-frame, shoes adapted to engage the said sleeves, a lever for manipulating the said 70 shoes, and a traveling carriage on which the said lever is fulcrumed, substantially as shown and described.

2. In a computing-scale, a weighing-beam, a platform, a connection between the weighing-beam and platform-frame, and comprising a sleeve held movable on the said weighing-beam, a sleeve held movable on the said platform-frame, shoes adapted to engage the said sleeves, a lever for manipulating the said 75 shoes, a traveling carriage on which the said lever is fulcrumed, a disk having a scale, and adapted to turn in unison with the longitudinal movement of the said carriage, and a pointer fixed on the said carriage and indicating on the scale on said disk, substantially 80 as shown and described.

3. In a computing-scale, the combination of a platform, a horizontal frame connected to said platform and arising above the same, 90 a slide movable on the platform-frame, a weighing-beam to which the slide is also connected, and an indicator-disk revolvably mounted on the slide and revolving as the same moves, substantially as described. 95

4. In a computing-scale, a platform, a horizontal frame above the same and connected thereto, a slide movable on the platform-frame, an indicating-disk revolvably mounted on the slide and revolving as the same moves, 100 a weighing-beam to which the slide is also connected, and a weight slidable on the weighing-beam and connected to the slide, substantially as described.

5. In a computing-scale, a weighing-beam, 105 a slide movable thereon, a platform-frame on which the slide is also movable, a platform to which the horizontal frame is rigidly connected, an indicating-disk revolvably mounted on the slide, and two guide-rails longitudinal with the platform-frame, and in which the slide is mounted, substantially as described. 110

6. In a computing-scale, a weighing-beam, a slide movable thereon, a platform-frame on which the slide is also movable, a platform 115 to which the platform-frame is rigidly connected, downwardly-projecting legs fixed to the slide, friction-wheels carried by the legs, and horizontal guide-rails longitudinal with the weighing-beam and carrying the friction-wheels, substantially as described. 120

7. In a computing-scale, a weighing-beam, a sleeve movable thereon, a platform-frame, a platform to which the platform-frame is rigidly connected, a sleeve movable on the platform-frame, a connection between the two sleeves, a shoe located under each sleeve and rigidly connected to each other, a carriage having a vertical opening therein, a stem movable in said vertical opening and connected to 125 130

the shoes, and a lever fulcrumed on the carriage and connected to the stem, substantially as described.

8. In a computing-scale, a stationary frame, 5 a platform carried by the frame, a platform-frame bar arising from the platform and rigid thereon, a weighing-beam fulcrumed on the the frame, a slide movable longitudinally on the weighing-beam and frame-bar, and an indicating-disk revolvably mounted on the slide and making contact with the frame, substantially as described.

9. In a computing-scale, the combination of a frame, a platform thereon, a platform-frame 15 bar connected to the platform and extended horizontally above the same, a weighing-beam fulcrumed on the frame, a sleeve slidable on the weighing-beam, a second sleeve slidable on the horizontal portion of the platform-frame 20 bar, a connection between the two sleeves, a shoe for each sleeve and rigidly connected to each other, means for clamping said shoes against the sleeves, and a counterbalancing-weight on the weighing-beam, substantially 25 as described.

10. In a computing-scale, the combination of a frame, a platform thereon, a platform-frame bar rigidly connected to the platform and extended horizontally above the same, a 30 weighing-beam fulcrumed on the frame, a sleeve slidable on the weighing-beam, a second sleeve slidable on the horizontal portion of the platform-frame bar, a connection between the two sleeves, means for clamping

said sleeves against their respective supports, 35 and a counterbalancing-weight on the weighing-beam, substantially as described.

11. In a computing-scale, the combination with a frame, a platform thereon, a platform-frame bar rigid on the platform and extended 40 horizontally above the same, a weighing-beam fulcrumed on the frame, a sleeve carried by the weighing-beam, a second sleeve carried by the horizontal portion of the platform-frame bar, a connection between said sleeves, 45 a shoe for each sleeve, the said shoes being rigidly connected to each other, a slide movable on the frame, a stem movable vertically in the slide and connected to the shoes, a lever fulcrumed on the frame and connected to the 50 stem, and a counterbalancing-weight on the weighing-beam, substantially as described.

12. In a computing-scale, the combination of a frame, a platform on said frame, a platform-frame bar rigid on the platform and extended 55 horizontally above the same, a weighing-beam fulcrumed on the frame, a sleeve slidable on the weighing-beam, a second sleeve slidable on the horizontal portion of the platform-frame bar and connected to the first 60 sleeve, and means for clamping the said sleeves on their respective supports, substantially as described.
